[57] CLAIM

The ornamental design for a liquid container, as shown and described.

DESCRIPTION

FIG. 1 is a perspective view showing our new design for a liquid container;

FIG. 2 is a side elevational view thereof, the opposed side being a mirror image thereof;

FIG. 3 is a top plan view thereof;

FIG. 4 is an end elevational view thereof taken from the right of FIG. 1;

FIG. 5 is a bottom plan view; and,

FIG. 6 is an end elevational view thereof taken from the left of FIG. 1.
